UNITED STATES PATENT OFFICE.

HERVEY EVELYN GAMBLE, OF LONDON, ENGLAND.

PNEUMATIC ACTION FOR AUTOMATIC MUSICAL INSTRUMENTS.

1,291,670.

Specification of Letters Patent. Patented Jan. 14, 1919.

Application filed June 4, 1917. Serial No. 172,657.

To all whom it may concern:

Be it known that I, HERVEY EVELYN GAMBLE, a subject of the King of Great Britain and Ireland, residing at 149 Albion road, Stoke Newington, London, N., England, have invented certain new and useful Improvements Relating to Pneumatic Actions for Automatic Musical Instruments, of which the following is a specification.

10 This invention relates to pneumatic actions for automatic musical instruments of the kind in which the valve controlling the striking pneumatic is operated by a diaphragm subject to the continued action of 15 the main exhaust and operated by the admission of air by way of the tracker bar port and in which the valve is disposed between two valve seats in a valve chamber superposed upon a chamber provided with the 20 diaphragm and in which passages or ports are provided to effect communication between the valve chamber and the striking pneumatic and between the diaphragm chamber and the vacuum chest.

25 The invention has for its object to provide an operating valve and valve casing for striking pneumatics, simple in construction and easily accessible for repair.

According to the invention the valve casing 30 is provided with a metal part detachable from the main part of the casing and unconnected with the striking pneumatic for application beneath the main part of the valve casing at the position where the chamber is 35 formed communicating with the exhaust, the said metal part being provided with a cavity or diaphragm chamber and serving to hold the diaphragm between its upper face and the lower face of the main part of the valve 40 casing and to communicate from beneath the diaphragm with the tracker bar.

The invention is illustrated in the accompanying drawings in which—

45 Figure 1 represents in sectional elevation a pneumatic action constructed according to the invention, while

Fig. 2 is a plan corresponding to Fig. 1.

In carrying the invention into effect according to one construction, I provide the 50 valve casing of metal in three parts a b and c , the main part or section a being centrally disposed and serving to carry at one end the port or passage a^1 by which communication

is made with the striking pneumatic d , a flange a^2 being provided at the lower end 55 of this part of the central section a of the valve casing by which the central section and the upper and lower sections or parts b and c carried by it may be mounted upon the upper or stationary member d^1 of the pneumatic. The central section a is provided with its upper and lower surfaces a^2 a^3 parallel. On the upper surface a^2 at one end the port or passage a^1 communicating with the pneumatic d emerges, while near 60 the other end a central hole and a valve seat a^4 are provided. On the underside an elongation cavity a^5 is formed which is advantageously of an oblong form, which communicates with the exhaust tube or chest e 65 by means of a port a^6 which extends to the opposite end of the central section where a flange a^7 is provided laterally extending on each side of the port, and by means of which communication may be made with the exhaust chest e . The flange a^7 is secured to the exhaust tube or chest e with an air tight 70 joint. Within the elongated cavity a^5 formed on the underside of the central section a and in a central position, an arm f 75 extends for the purpose of carrying the lower end of the valve spindle g^1 within a hole in the arm f which is concentric with the valve seat.

The arm f is secured in position on the 80 under side of the section a by means of a single screw h , its position being determined by means of parallel ribs a^8 by which a cavity is formed on the under-side of the section within which the arm f fits so that 85 thus the arm f is set into exact position and fixed in that position by the use of a single screw.

The upper section b of the valve casing is provided as an elongated cover plate which 90 extends to the rear, and on the underside is formed with a cavity b^1 which extends to cover over the passage or port a^1 in the central section a communicating with the striking pneumatic d , so that thus a chamber 95 is formed which extends from one end of the casing at which the port or passage a^1 emerges leading to the pneumatic d , to the other at which the valve g is mounted, and at this end a hole b^2 is formed in the upper 100 section b corresponding in size and position

- to the hole a^4 formed for the valve seat of the valve g in the central section a ; and on the upper face of the upper section b an arm h extends into or over this hole b^2 to 5 a central position in coincidence with the protruding arm f provided on the under side of the central section a , and these respective arms h and f serve to carry the upper and lower ends of the valve spindle 10 g^1 and to guide the spindle in the movement of the valve g from its seat upon the top of the central section a of the casing to its seat upon the underside of the upper section b thereof. These respective arms h 15 and f may be integrally provided with their respective sections. I prefer, however, to provide the arm h separate from the section b and to set the arm h in position by means similar to that by which the arm f is set. 20 For this purpose parallel ribs b^8 are provided upon the upper face of the section b of the casing to form a recess within which the arm h may fit so that thus the arm h may be set into its exact position for carrying the spindle g^1 by means of a single screw l . The single screw l may at the same time serve for securing the upper section b to the lower section a . For this purpose a boss b^4 is provided protruding on the 25 underside of the section b , which on the section b being placed in its proper position upon the section a lies in contact with the face a^2 . By such means the section b is secured in its proper position upon the section a by a single screw which at the same 30 time serves to set the arm h in position to register with the arm f . The section b may be provided at one end, that is to say at the end near the exhaust 40 pipe e with a lug b^3 , a corresponding recess being formed immediately beneath for the accommodation of the boss a^9 provided upon the upper face of the section b . The front edge of this boss a^9 may be provided with 45 a circular face of a curvature corresponding to the circular face of the front end of the section b so that thus when the section b is placed in position upon the section a it readily assumes its central position in register with the lower section. Any other means 50 may, however, be provided to insure the register or alinement of the upper section b at one or other end. Or again another screw may be provided to secure the lug c^3 to the boss a^9 . The section b is secured to the section a by a metal to metal joint which may be rendered tight by the application upon the jointing faces of sheet of packing secured 60 by a solution of shellac or by any other means. The lower section c of the casing is provided for the reception on its upper face of a leather or other diaphragm i and is provided 65 with a cavity c^1 beneath the dia-

phragm i which communicates with the port c^2 leading to the end of the section. The end of the section is provided with a flange c^3 for connection with the end of the exhaust duct leading to the tracker bar. The 70 exhaust duct is thus connected to the lower section by a metal to metal joint which may be rendered air tight by means usually employed.

I claim:

1. In a pneumatic action for automatic musical instruments in combination, a valve casing of metal connected at one end to the exhaust and at the other end to the stationary member of the striking pneumatic, the 80 said valve casing being provided with a chamber communicating with the exhaust, a metal part detachable from the main part of the valve casing and unconnected with the striking pneumatic for application between the main part of the said valve casing and the striking pneumatic, the said metal part being provided with a diaphragm chamber and serving to hold the diaphragm between its upper face and the lower face of 85 the valve casing and to communicate from beneath the diaphragm with the tracker bar, substantially as described.

2. In a pneumatic action for automatic musical instruments in combination, a valve 90 casing of metal connected at one end to the exhaust chest and at the other end to the stationary member of the striking pneumatic, said valve casing having a chamber communicating with the exhaust, a metal 95 part detachable from the main part of the valve casing and unconnected with the striking pneumatic for application between the main part of the said valve casing and the striking pneumatic, said metal part being provided with a diaphragm chamber and serving to hold the diaphragm between its upper face and the lower face of 100 the valve casing and to communicate from beneath the diaphragm with the tracker bar, substantially as described.

3. In a pneumatic action for automatic musical instruments in combination, a valve 110 casing of metal connected at one end to the exhaust chest and at the other end to the stationary member of the striking pneumatic, said valve casing having a chamber communicating with the exhaust, a metal 115 part detachable from the main part of the valve casing and unconnected with the striking pneumatic for application between the main part of the said valve casing and the striking pneumatic, the said metal part being provided with a diaphragm chamber and serving to hold the diaphragm between its 120 upper face and the lower face of the valve casing and to communicate from beneath the diaphragm with the tracker bar, substantially as described.

125

130

upper face and the lower face of the valve casing and to communicate from beneath the diaphragm with the tracker bar, a metal cover plate having on its underside a cavity 5 adapted to extend over and upon said valve casing from one end at which the passage emerges leading to the pneumatic to the other at which the valve is mounted, and means for carrying the valve comprising arms fitted within recesses formed by ribs 10 on the main part of the casing and on the cover plate respectively, substantially as described.

HERVEY EVELYN GAMBLE.
